Primary Examiner — Barbara Fox(74) *Attorney, Agent, or Firm* — Barnes & Thornburg LLP**CLAIM**

The ornamental design for a display device, as shown and described.

DESCRIPTION

FIG. 1 is an isometric view of a display device from the front showing our new design,

FIG. 2 is a front elevational view thereof,

FIG. 3 is an isometric view from the rear thereof,

FIG. 4 is a rear elevational view thereof,

FIG. 5 a top plan view thereof,

FIG. 6 is a bottom plan view thereof,

FIG. 7 is a left side elevational view thereof; and,

FIG. 8 is a right side elevational view thereof.

The broken lines shown in the drawings represent portions of the display device that form no part of the claimed design.
